UNITED STATES PATENT OFFICE.

LAURENCE S. LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,378,876.

Specification of Letters Patent. Patented May 24, 1921.

Application filed June 3, 1919. Serial No. 301,458.

To all whom it may concern:

Be it known that I, LAURENCE S. LACHMAN, a citizen of the United States, and a resident of New York, in the county of New

5 York and State of New York, have invented certain new and useful Improvements in Metal Wheels, of which the following is a specification.

My invention relates to metal wheels 10 wherein two metal plates or disks arranged side by side and suitably secured together either with or without an interposed rigid central frame or spider are used for the body or spoke part of the wheel and carry at 15 their circumferential edges a metal rim seated upon said disks and wherein a reinforcement is interposed between the circumferential edges to strengthen the felly portion of the structure.

20 My invention relates more particularly to the reinforcement and manner of supporting and combining the same with the disks or plates, the object being to simplify the construction, diminish the number of parts 25 required and to afford a practically uniform reinforcement or support for the rim through its whole circumference, so as to avoid the tendency or the liability to the formation of flat spots in the running of 30 the wheel, and which are liable to form in previous constructions wherein isolated reinforcing pieces are employed bridging the edges of the side plates or disks, as in the construction described in the prior application 35 of Maurice Lachman filed November 2nd, 1917, Serial No. 199,828.

Other objects and advantages secured by my improved construction will appear from the subjoined description.

40 To these ends my invention consists essentially of a reinforcement comprising an annular plate interposed between the edges of the disks and supported between them, said annular plate having a radially projecting continuous rib engaging the inner surface of the rim.

The invention further consists in the continuous annular reinforcement for the rim supported upon circumferential ledges near 50 the edge of the disks and welded to said ledges.

My invention also consists in the details of construction as more particularly herein-after described and then specified in the 55 claims.

Figure 1 is a side elevation of a complete wheel constructed in accordance with my invention, a portion of one of the side plates being broken away.

Fig. 2 is a vertical section on the line 2—2 of Fig. 1 and

Fig. 3 is a cross-section on the line 3—3 Fig. 1.

1 indicates the side plates or disks of the construction each formed near its edge with 65 a circumferential ledge or shoulder as indicated at 2. 3 indicates a metal rim seated upon the circumferential edges 2 of the disks arranged, as shown in the section, side by side and properly secured together or to 70 an interposed rigid frame or spider comprising metal bars or spokes of the manner described in the prior application above referred to. The inner edges of said disks may be turned inward to form the barrel or portion 75 of the barrel of the hub structure and metal hub plates or flanges 6 may be also used, suitable fastening bolts being passed through said strengthening hub flanges, all as described in the prior application.

80 4 indicates spokes of the rigid central frame or spider which it is desirable to employ for strength. These, as described in the prior application above referred to, consist preferably of flanged metal bars the 85 flanges of which afford a bearing for the side plates. Said flanged metal bars may be, as indicated, channel bars or other desired shape. These flanged metal spoke members of the structure preferably seat at 90 their inner ends upon the hub part and at their outer ends engage the inner surface of a circumferential reinforcing plate 5. The side plates may be spot welded to the bars at any desired number of points as also described in the prior application above referred to.

95 My present invention relates particularly to the feature of the annular reinforcing plate 5 which, as shown, is interposed between the disks near their circumferential edge and is itself supported upon the ledges or shoulders 2. Said reinforcing plate 5 has preferably the circumferential rib or projection 5' at or near its center engaging the 100 inner surface of the rim 3, thereby affording a continuous support for the intermediate portion of the rim between its edges.

105 In the previous construction described in the prior application the reinforcement com- 110

prises a series of separate reinforcing plates extending across from one disk to the other in the spaces between the spokes 4, so that there is a liability to the formation of flat spots in the rim at points between the points of support afforded by the reinforcement. The construction provided by my present invention avoids this difficulty. In the previous construction the extreme edges of the disks are turned over into a flange upon which the rim rests but in my present invention the rim rests directly upon the edges and an open space is left through which the annular reinforcement 5 may be spot welded to the ledges 2, if desired, to fasten them together and hold the parts against relative displacement circumferentially.

When the rigid bar metal spoke structure is employed it is obvious that the same may take many different forms other than that specifically described without departing from my invention.

What I claim as my invention is:—

1. In a wheel of the character described, 25 the combination of a pair of side disks or plates provided with offsets or ledges at their circumferential edges, a rim seated upon the edges and a reinforcement of hollow cylindrical form seated upon said edges

and having a radially projecting continuous 30 rib engaging the inner surface of the rim.

2. In a metal wheel of the character described the combination with a pair of side plates having outwardly projected flanges near their circumference, a reinforcement 35 of hollow cylindrical form seated upon said edges and welded thereto and a rim seated upon the circumferential edge of said plates.

3. In a wheel of the character described, 40 the combination of a pair of side plates provided with ledges or shoulders near their circumference, a metal rim seated upon said side plates, a continuous annular reinforcement having an externally projecting rib 45 engaging the rim between the points of engagement thereof with the side plates and seated upon the said ledges and a rigid spoke member engaging the inner surface of said annular reinforcement. 50

Signed at New York, in the county of New York and State of New York, this 29th day of May, A. D. 1919.

LAURENCE S. LACHMAN.
